US0D1071202S

(12) **United States Design Patent** (10) **Patent No.:** **US D1,071,202 S**
(45) **Date of Patent:** **** Apr. 15, 2025**

(54) **PORTABLE MEDICAL MONITOR CONNECTOR**

- (71) Applicant: **AMBU A/S**, Ballerup (DK)
- (72) Inventor: **Line Sandahl Ubbesen**, Holte (DK)
- (73) Assignee: **AMBU A/S**, Ballerup (DK)
- (**) Term: **15 Years**
- (21) Appl. No.: **29/895,379**
- (22) Filed: **Jun. 21, 2023**

Related U.S. Application Data

- (60) Continuation of application No. 29/812,248, filed on Oct. 20, 2021, now Pat. No. Des. 994,882, which is a division of application No. 29/725,076, filed on Feb. 21, 2020, now Pat. No. Des. 937,412.

(57) **CLAIM**

The ornamental design for a portable medical monitor connector, as shown and described.

DESCRIPTION

FIG. 1 is a front perspective view of a portable medical monitor connector showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Uniformly-sized broken lines illustrate features of the portable medical monitor connector that form no part of the claimed design. Long-short broken lines illustrate boundaries of the claim and form no part of the claimed design.

1 Claim, 6 Drawing Sheets
